UNITED STATES PATENT OFFICE.

ALBERT S. DEHLER, OF MINNEAPOLIS, MINNESOTA.

GRAVITY-CONVEYER.

No. 867,350.

Specification of Letters Patent.

Patented Oct. 1, 1907.

Application filed December 28, 1906. Serial No. 349,856.

To all whom it may concern:

Be it known that I, ALBERT S. DEHLER, a citizen of the United States, residing at Minneapolis, in the county of Hennepin and State of Minnesota, have 5 invented certain new and useful Improvements in Gravity-Conveyers; and I do hereby declare the following to be a full, clear, and exact description of the invention, such as will enable others skilled in the art to which it appertains to make and use the same.

10 My invention relates particularly to so-called "gravity carriers" or "conveying systems", and has for its object to improve the same in the several particulars hereinafter noted.

The invention consists of the novel devices and combinations of devices hereinafter described and defined 15 in the claims.

In the accompanying drawings which illustrate the invention, like characters indicate like parts throughout the several views.

20 Referring to the drawings, Figure 1 is a plan view, showing a portion of a gravity carrier or conveyer embodying the features of my invention. Fig. 2 is a side elevation of the parts shown in Fig. 1. Fig. 3 is a view partly in elevation, but chiefly in vertical section 25 on the line $x^3 x^3$ of Fig. 1, some parts being broken away. Fig. 4 is a view partly in elevation and partly in section on the line $x^4 x^4$ of Fig. 1, some parts being broken away. Fig. 5 is a transverse section on the line $x^5 x^6$ of Fig. 4. Fig. 6 is a perspective view, showing 30 two abutting roller supporting rails separated from each other; and Fig. 7 is a detail in section illustrating a slightly modified form of one end of one of the rollers.

The numeral 1 indicates the roller supporting rails or bars which are spaced apart but rigidly connected at 35 suitable intervals by transverse tie bars 2 and truss bars 3. In the straight sections of the track are mounted cylindrical rollers 4, and in the curved sections thereof are mounted tapered rollers 5, which rollers are above the tie bars 2 and truss bars 3. The rails 1 are preferably formed in sections, which sections are connected 40 by interlocking joints, best shown in Fig. 6, by reference to which it will be seen that of the abutting ends of the two rails, one is provided with reversely extended laterally offset upper and lower lock lugs 6 and 7 45 stamped from the body thereof. The adjacent end of the other rail or bar is laterally offset at 8 and is provided at its lower edge with a notch 9. The offset portion 8 is adapted to enter between the inner faces of the lock lugs 6-7 and the face of the rail or bar from 50 which they are pressed, while the notch 9 is adapted to straddle the base of the lower lug 7, as clearly shown in Fig. 2, and thus rigidly interlock the two rail or bar sections.

The rollers 4 and 5 are connected to the rails 1 by 55 ball bearing devices which in this preferred arrange-

ment include ball receiving sockets 10 that are forced under pressure into seats or large perforations 10^a formed in the rails 1. At the other inner extremities the ball receiving sockets 10 are provided with central perforated caps 11, the edges of which are clenched 60 or bent over the outwardly flaring edges of the said sockets. The bearing balls 12 are confined in an annular run-way formed between said cap 11, the largest portion of the said socket 10, and an in-pressed 65 annular shoulder 13 of the said socket.

70 The cylindrical rollers 4 are preferably constructed as best shown in Fig. 3, with out-turned end flanges 4^a over which are bent the outer edges of roller heads 14. These roller heads 14 are centrally perforated to pass the body portions of trunnions 15, which trunnions have 75 slightly reduced ends or journaled portions 16 and bevel heads 17. The bevel heads 17 of said trunnions are securely clamped between the inset portions of the roller heads 14, and clamping plates 18 rigidly secured to said rollers by suitable devices, such as rivets 19. 75 The reduced journaled portions 16 of said trunnions project into the corresponding sockets 10 and run upon the balls 12 that are confined within said sockets.

80 The tapered rollers 5 are of novel construction. They are made from tapered metal plates rolled into proper form and provided with abutting in-turned edges 5^a, and with out-turned annular end flanges 5^b. With these tapered rollers, the annular roller heads 14 are preferably applied the same as already described in connection with the rollers 4, that is, the out-turned 85 edges thereof are bent over and around the said flanges 5^b, thereby holding the ends of the said tapered rollers in the proper form. The abutting in-turned longitudinal flanges 5^a have close joints and strengthen the rollers at what would otherwise be their weakest points, 90 to-wit, at their adjoining edges of the rolled metal sheet which constitutes the body thereof. The arrangement of the trunnions and ball bearing devices for the tapered rollers is the same as that described in connection with the cylindrical rollers.

95 Fig. 7 illustrates a modification of the cylindrical roller in which the end thereof is provided with an impressed annular groove 20 between which and the in-turned end flange 21 of which roller is clamped a roller head made up of an annular plate 22 and a disk 23, 100 which parts are connected by rivets 24, and as before described, hold the tapered heads 17 of the trunnion 15.

105 The device described, while of small cost, is capable of being very quickly put together and is highly efficient for the purposes had in view

What I claim is:

1. The combination with roller supporting rails or bars, of sockets 10 held in the seats formed in said rails or bars and provided with roller heads 11 clenched to the inner edges thereof, of rollers provided with projecting 110

trunnions working in said sockets 10, and bearing balls interposed between said trunnions and sockets, substantially as described.

2. The combination with supporting rails or bars and ball equipped sockets held in the seats formed therein, of rollers having heads interlocked with the end portions thereof, and headed trunnions interlocked with said roller heads, and journaled in said ball equipped sockets, substantially as described.
- 5 3. The combination with a roller having a flange at its end, of a roller head interlocked with the end flange of said roller, and a headed trunnion seated in and held by said roller head, substantially as described.
- 10 4. A roller comprising a rolled sheet metal body having

flanged ends, and abutting longitudinally extended edges, 15 and roller heads interlocking with the end flanges of said roller, substantially as described.

5. A roller comprising a rolled metal body portion having abutting in-turned longitudinally extended edges 5^a and out-turned end flanges 5^b, and roller heads having 20 flanges bent or clenched around said end flanges 5^b, substantially as described.

In testimony whereof I affix my signature in presence of two witnesses.

ALBERT S. DEHLER.

Witnesses:

MALIE HOEL,

F. D. MERCHANT
